UNITED STATES PATENT OFFICE.

NORMAN B. HURD, OF NEW BRITAIN, CONNECTICUT, ASSIGNOR TO AMERICAN HARDWARE CORPORATION, OF NEW BRITAIN, CONNECTICUT, A CORPORATION OF CONNECTICUT.

LOCK.

1,368,727.

Specification of Letters Patent. Patented Feb. 15, 1921.

Application filed December 11, 1918. Serial No. 266,196.

To all whom it may concern:

Be it known that I, NORMAN B. HURD, a citizen of the United States of America, residing at New Britain, Connecticut, have 5 invented a new and useful Lock, of which the following is a specification.

My invention relates to door locks and particularly locks of the type in which there is a spring latch bolt provided, which latch 10 bolt is alone so controlled that it may likewise perform the function of a dead bolt.

My present invention is essentially an improvement on the construction set forth in my former Patent #1,168,725, dated January 18, 1916. In the present case as well 15 as in the lock shown in my said earlier patent, a single key standing in a single key-hole at the outside of the door may be used to perform any one of the following functions:—

First:—It may be used as a means to retract the latch bolt at any time.

Second:—It may be used as a means to set or throw off certain stop work, whereby the 20 outside knob or thumb-piece may be rendered ineffective at certain times, so that the latch cannot be retracted thereby.

Third:—It may be used for the purpose of operating hold back mechanism, whereby 25 the latch bolt when in a retracted position may be locked back in that position during certain hours when it is desired to leave the door not only unlocked but unlatched, so that it may be freely pushed open.

The arrangement of parts in the present 30 case is such that when said key is operated to retract the latch, there is no danger of operating the stop work mechanism, or vice versa, the functioning of said parts being wholly independent. In the lock of my former patent if the said key is rotated in a 35 direction to retract the latch, it will also perform the function of throwing off the stop work, so as to permit access thereafter by the mere turning of the outer knob. Inasmuch as there may be occasions when it is 40 desirable to enter the building by means of a key from the outside without throwing off the stop work, my present invention contemplates the construction and arrangement of 45 parts which will permit the key to be turned in a direction to retract the latch without throwing off the stop work, the throwing off

of the stop work requiring reverse movement of said key. By this means, I am enabled to accomplish with a single pass key so-called, all of the functions that were accomplished by the use of a master key in my former patent, and I furthermore gain the advantage last described of permitting the door to be opened from the outside by means of a key when the stop work is on, without throwing off said stop work. This arrangement of parts likewise makes it possible to employ a single cylinder lock roll back of 60 conventional form, instead of the special form preferably employed in a lock such as set forth in my aforesaid patent, thereby somewhat cheapening the cost of construction. Whereas in the former lock construction, it was only the holder of a master key 65 that could perform all of the aforesaid functions, I now make it possible for the holder of an ordinary key to perform all of these functions. It will also be noted that by the 70 arrangement of parts hereinbefore described, all of these movements may be effected by said single key and said single conventional cylinder roll back without any 75 danger of inadvertently performing more 80 than the one intended function at a time.

In the drawings, I have shown one preferred form of my invention.

Figure 1 is a view illustrative of the interior of a lock with the outer side of case 85 removed to show the working parts. In this view the parts are shown associated with a strike plate and the mechanism is set in a position to prevent the picking back of the latch from the outside, and in this position 90 also the outside hand operated roll-back is dogged by a so-called stop work device.

Fig. 2 is a similar view of certain parts in another position, that is to say the position in which they would appear when the key is 95 turned to retract the latch.

Fig. 3 is a similar view of said parts in still another position, the key being here shown as turned backwardly to throw off the stop work and release the outside roll 100 back.

Fig. 4 is a similar view of said parts when the same are in position to hold the latch retracted so as to leave the door with which the lock is associated entirely free to be 105 pushed open.

Fig. 5 is a detailed view of certain parts detached from Fig. 1 and showing said parts in the same position.

Fig. 6 is a detail view of the same parts 5 in the latch dogging position of Fig. 4.

Fig. 7 is a view of an ordinary cylinder lock with the key in place.

1 represents the lock case. 2 is a spring latch bolt projected through the face plate 10 3 of the lock. 4 represents a strike plate having the usual opening to receive the latch bolt 2 when the door is closed. 5 represents an automatic controller having the usual beveled nose which is arranged to be 15 repressed by contact with the strike plate 4 and to be held back thereby whenever the door is closed, the function of this controller being later described. 6 is a latch retracting lever pivotally mounted at 7 in the lock case 20 and arranged to be operated by a key, in this case the key being of the flat type for operation of a cylinder lock 8, the cylinder lock being mounted on the outer side of the lock case in the usual manner. This cylinder lock carries the conventional roll back 25 9 at the inner end of the rotatable key plug, so that by rotating the key plug and the roll back 9 from the position shown in Fig. 1 to the position shown in Fig. 2, the latch 30 2 may be retracted by the key, as shown in the last mentioned figure. In this particular instance, there is a swinging lever 10 pivoted at 11 in the case against which the cylinder roll back 9 strikes, the free end of 35 35 the lever 10 bearing against an offset shoulder on the retracting lever 6, whereby when said key is turned as described, it will have the effect of retracting the latch 2. 12 is an ordinary roll back mounted in the case 1. 40 This roll back is designed to be operated by an ordinary knob (not shown) in the inner side of the door, and hence we will refer to this roll back as the inside roll back. In this instance, the arm of the roll back 12 45 engages the end of lever 6 so that when the latch 2 is retracted by the roll back 12 it is effected through the medium of lever 6. 13 is a cross head or plate at the rear end of the latch bolt 2 against which the end of 50 lever 6 operates. 14 is the usual swinging roll back pivoted at 15, the other end of said roll back engaging lever 6 so that when the roll back 14 is swung back on the pivot 15, it will in turn retract the latch. This swinging roll back 14 is preferably operable by 55 what is known as a thumb piece (not shown), said thumb piece engaging the under side of the roll back 14 through a notch 16 in the lower edge of the case, this form 60 of construction being very well known. We will refer to the roll back 14 as the outside roll back.

17 is a stop-work lever which is designed to either engage or free the outside roll back 65 14. This lever is pivoted at 18. In Fig. 1

the stop work lever 17 is shown as engaging and dogging the outside roll back 14, whereas in Fig. 3, it is shifted back or thrown off to a position where this roll back 14 is free.

19 is a lever pivoted at 20 and having one 70 end 21 adapted when in the position shown in Fig. 1, to stand back of the projected latch bolt 2 so that the latter cannot be picked back by a tool inserted between the face plate 3 and the strike plate 4. This 75 lever 19 has another arm 22 which is inclined, as shown, so that when a stud 23 on the rear end of the controller 5 stands in the position shown in Fig. 1, (wherein the controller 5 is retracted), it will allow the lever 80 19 to swing down into the latch dogging position therein shown. When, however, the controller 5 is projected, as shown in Figs. 3 and 4, the stud 23 will engage the arm 22 and lift the end 21 so as to free the latch 85 bolt 2.

24 is a swinging lever pivoted on stud 7 and having the two offsets 26—27. At the lower end of the lever is a pin 28 which projects into a curved slot 28^a in a second lever 29, the latter being pivoted on a stud 30 on the upper end of the stop work lever 17. The free end of the lever 29 is located and is slidable under the shoulder for the pivot stud 20, so that it cannot tilt up beyond that 95 limit. The lower edge of the free end of said lever 29 rides along the upper edge of the cross head 13 whenever the lever 29 is given a sliding movement. At all times excepting when the latch 2 is dogged back as 100 hereinafter described, the pin 28 stands in the lower part of the curved slot in the lever 29, as shown in Figs. 1, 2, 3 and 5.

It is important to note that this cam slot 28^a pitches down toward the face plate of 105 the lock. That is to say, the pitch of this cam slot is in an opposite direction to the corresponding cam slot shown in the lock of my former patent.

In the body of the lever 19 is an opening 110 31 of a general triangular outline and into this opening projects the end of the stud 30 which is preferably flattened or otherwise suitably shaped to work to advantage therein. Assuming the various parts stand as 115 shown in Fig. 4, this stud 30 will, by co-operation with the inclined upper edge of the opening 31, lift or support the free end 21 of the latch dogging lever 19 and hold it in this lifted position even though the controller 5 be retracted.

It is important to note that this opening 31 is arranged reversely to that shown in my former patent, that is to say the narrower part of said opening is toward the 125 face plate 3.

32 is a shoulder on the latch retracting lever 6 which also co-operates with the lower edge of the latch dogging lever 19 in such a way that whenever the lever 6 is retracted, 130

by any of the roll-backs 9, 12 or 14, the first part of the movement will quickly lift the latch dogging lever 19 so as to remove it from behind the latch before the continued 5 rearward movement of the lever 6 retracts the latch.

Operation.

Starting with the parts as shown in Fig. 1, which shows the lock as it would appear 10 when the door is closed and the outer roll back 14 is dogged against operation by the stop work lever 17, it is apparent that access from the outside can now be had only 15 by key. By inserting a key into the cylinder lock and turning the cylinder roll back 9 toward the lever 10, the said roll back will depress the lever 10, which by reason of its engagement with the latch retracting lever 6, 20 will swing the lever so as to retract the latch to the position shown in Fig. 2, so that the door may be opened. It will be noted that this act may be accomplished without disturbing the stop work, hence, anyone who 25 gains entry in this manner may thereafter close the door with the knowledge that the stop work is still on so as to prohibit entry thereafter, excepting by a key.

If it is desired to throw off the stop work, 30 the same key while standing in the same key-hole may be used to turn the cylinder roll back 9 in a reverse direction from that first described, until it assumes the position indicated in Fig. 3. This movement of the 35 key causes the cylinder roll back 9 to engage the shoulder 27 on the lever 24, so as to swing the latter in a direction to move the slide 29 toward the face plate 3 of the lock. Since the slide 29 is connected to the upper 40 end of the stop work lever 17, it moves the lower end of the latter from the dogging position indicated in Fig. 2, to the "off" position indicated in Fig. 3. In my former 45 patent, it will be recalled that when a master key is used (which by the way, is the only key which can be employed in that lock to set the stop work), the turning of that key in the direction to retract the latch, also incidentally releases the stop work. In the 50 present case to avoid the releasing of the stop work by such a movement, I have so constructed the parts that it requires a reverse rotation of the key for that purpose, so that the stop work will never be thrown 55 off unintentionally.

Assuming it is desired to hold the latch bolt retracted for certain periods, so that the door may be freely pushed open, as is frequently desirable when such locks are employed on the exit doors of schools, stores, or 60 public buildings, the following steps are taken:

First, the cylinder roll back 9 is turned so as to throw off the stop work, causing the 65 parts to stand as shown in Fig. 3. When this

occurs, the rear end of the slide 29 will stand sufficiently far advanced, so that when the latch bolt 2 is pushed back, the cross-head 13 will move to the rear of the rear end of said slide as indicated in dotted lines, thereby 70 permitting the rear end of the slide 29 to be tilted down to the position shown in Figs. 4 and 5, wherein the rear end of said slide will block the advance of the latch. This tilting down of the rear end of the slide 29 is effected 75 by merely turning the key control roll back 9 as far as possible in the first mentioned direction, that is to say, in the direction to engage the lever 10, whereby, through the medium of the latter which engages the 80 shoulder 26 on the lever 24, the pin 28 will be caused to ride along the lower edge of the cam slot 28^a, so as to force the rear end of the slide lever 29 downwardly into the latch hold back position, plainly shown in Figs. 4 85 and 6. It is obvious that it is impossible to throw the lever slide 29 down to this position, excepting when it has been first advanced to the position wherein the stop work lever is thrown "off," because at all other 90 times the rear end of the slide lever 29 will stand over the cross-head 13, even when the latter is fully repressed, as shown in Fig. 2.

It should be noted that whenever the latch retracting lever is swung back, the first part 95 of this movement causes the shoulder 32 on said retracting lever to engage the bevel on the latch dog lever 19, so as to lift the latter out of the way of the latch bolt, whereby a continued rearward movement of 100 the retracting lever 6 may retract the latch. It should also be noted that whenever the stop work 17 is "off," the latch dogging lever 19 is also off, the latter being lifted by the pin 30 acting on the beveled upper wall of 105 the opening 31 (see Fig. 3). At all such times, it is, of course, unnecessary to dog the latch against being picked back, because at such times the latch may be retracted by merely operating the outer roll back 14 110 which is then free.

It will be understood of course, that the cylinder lock is mounted in the side plate of the lock case which has been removed from the several figures of the drawings. In 115 the claims, for convenience of expression, I may refer to the roll-back 9 as the key roll-back, or cylinder lock roll-back, this device in reality constituting in effect the inner end of the key itself when the latter 120 is in place in the cylinder lock and therefore operating the same as would the bitted end of an ordinary key. I mention this because it is perfectly obvious that under certain conditions it might be possible to use an ordinary key for operating the internal parts instead of perfecting said operation through the medium and with the assistance of a pin cylinder lock. I have not attempted to describe the various springs employed to im- 130

part movement to the various internal pieces. In the main, all of said springs are shown and their operation is obvious. It will be understood, that by the construction herein described, anyone holding a key which will operate roll-back 9 may, with an understanding of the lock, use that same key to perform all of the various functions herein described thereby obviating the necessity of another special key for that purpose and without transferring the said key to any other cylinder lock or key passage.

What I claim is:

1. In a lock, a case, a spring latch bolt, a manually operable roll back for retracting said latch bolt from the outer side of a door to which the lock is applied, a latch retracting lever within said case, and operable by a key inserted from the outside in a key passage and turned in one direction, a stop work device for dogging said roll back, said stop work device being movable to the "on" position by the said key standing in the same key passage and turned in the aforesaid direction, and being moved to the "off" position by a reverse turning movement of said key in said passage.

2. A structure such as specified in claim 1 in combination with a so-called cylinder lock in which said key passage is formed, said cylinder lock including a rotatable plug with a roll back arm at the inner end thereof.

3. A structure such as specified in claim 1 in combination with a latch hold back device to hold said latch in its retracted position, said hold back device being operatively associated with said stop work mechanism, and being operable for holding back the latch only when the said stop work mechanism is "off," and only when said key is rotated in a direction reverse to that required for retracting the latch.

4. A structure such as specified in claim 3 in combination with a latch dogging device for holding the latch projected when the door is closed and the stop work is on, with means associated with the latch retracting mechanism to throw off said dogging device when the latch is retracted by said key.

5. A structure such as specified in claim

4 in combination with a connection between said stop work and said dogging device, whereby when said stop work is "off" said dogging device is "off."

6. In a lock, a case, a spring latch bolt, a roll back manually operable from the outside of the door to which the lock is applied for retracting said latch, a stop work device for engaging said roll back to prevent the operation thereof at certain times, a key actuated latch retracting lever separate from said stop work but operable simultaneously therewith by a single key when the latter is turned in one direction, whereby said latch may be retracted, and said stop work thrown to the "on" position by the said movement of said key, said stop work being thrown "off" by a reverse rotation of said key.

7. A structure such as specified in claim 6 in combination with a latch hold back device independent of said latch retracting lever but associated with said stop work, and operable only when said stop work is "off" and after said latch has been repressed, said hold back device at such a time being operable by turning said key in the aforesaid latch retracting direction.

8. In a lock, a case, a latch bolt movable therein, means for normally projecting the latch bolt, a single cylinder lock having a single roll back arm for co-operation with the internal parts of said lock, means operable by said cylinder roll back to retract the latch bolt, and means independent of said retracting means for holding said latch in its retracted position by the operation of the same cylinder roll back, a roll back for manually retracting said latch from the outer side of the door, a stop work for said roll back, separate from said latch retracting means, and operable by the same cylinder roll back, to be thrown to the "on" position by a turning movement of the key in the cylinder lock in a direction to retract the latch, and arranged to be thrown to the "off" position by said cylinder roll back when the latter is turned in the opposite direction.

NORMAN B. HURD
